Patented Nov. 3, 1885.

UNITED STATES PATENT OFFICE.

JAMES LYALL, OF NEW YORK, N. Y.

DESIGN FOR A CARPET.

SPECIFICATION forming part of Design No 16,362, dated November 3, 1885.

Application filed June 25, 1885. Serial No. 169,774. Term of patent 7 years.

To all whom it may concern:

Be it known that I, JAMES LYALL, of the city and State of New York, have invented and produced a new and original Design for 5 Carpets, of which the following is a specification.

This design for a carpet is shown in the annexed photograph.

The prominent features of this design are 10 the stripes A A and intermediate stripes, B B, both of said stripes being composed of checks, the alternate checks having diagonal lines in one direction, and the intermediate checks having diagonal lines in the other direction; 15 and these stripes A A are traversed by narrower stripes through the central portion thereof, as shown, and the stripes B B are

traversed by narrower stripes across their entire face, except at the central portion thereof, as shown and represented in the photograph. 20

I claim—

The design for a carpet consisting of the stripes A A and B B, composed of checks, and containing narrower stripes through the central portion of the stripes A A and across 25 the face of the stripes B B, except the central portion thereof, as shown in the photograph.

Signed by me this 19th day of June, A. D. 1885.

JAMES LYALL.
